COMBINED OIL TANK AND MOUNTING MEANS FOR A MOTORCYCLE

Jerry F. Morris, 220 S. Roselle Road,
Schaumburg, Ill. 60172

Filed Dec. 27, 1972, Ser. No. 318,726

Term of patent 3½ years

Int. Cl. D12—11

U.S. Cl. D23—2

FIG.2

FIG.4

FIG. 1 is a side elevational view of a combined oil tank and mounting means for a motorcycle, showing my new design, the opposite side being substantially a mirror image thereof;

FIG. 2 is a perspective view thereof;

FIG. 3 is a top plan view thereof; and

FIG. 4 is a rear elevational view thereof.

The broken lines shown in FIG. 1 are for illustrative purposes only.

I claim:

The ornamental design for a combined oil tank and mounting means for a motorcycle, substantially as shown and described.
